UNITED STATES PATENT OFFICE.

JEAN LOUIS BOULAY, OF PARIS, FRANCE.

DESIGN FOR A JEWEL-CASKET.

SPECIFICATION forming part of Design No. 22,641, dated July 18, 1893.

Application filed April 20, 1893. Serial No. 471,220. Term of patent 3½ years. Patented in France January 14, 1893, No. 3,071.

To all whom it may concern:

Be it known that I, JEAN LOUIS BOULAY, merchant, a citizen of the Republic of France, residing at 23 Rue des Filles du Calvaire, Paris, France, have invented and produced a new and original Design for Jewel-Caskets, (for which I have obtained Letters Patent in France, dated January 14, 1893, No. 3,071,) of which the following is a specification, reference being had to the accompanying drawings, forming a part thereof.

Figure 1 is a front elevation of a jewel casket made in accordance with my design, the casket being closed. Fig. 2 is a similar view, the lid of the casket being raised.

My design for jewel caskets, comprising a body, base and cover, forms the representation of a caravel floating upon a conventional representation of billows supported upon a

base or plinth having at the front a shield or scroll upon which a suitable inscription may be placed. The superstructure or deck to which the rigging, &c., is attached, is so arranged with relation to the hull of the caravel as to at times disclose an aperture or receptacle-like compartment contained therein, as shown in Fig. 2.

I claim—

The design for a jewel casket, substantially as shown and described.

In testimony that I claim the foregoing as my design I have signed my name, in presence of two witnesses, this 6th day of April, 1893.

JEAN LOUIS BOULAY.

Witnesses:

ALBERT MOREAU,
CHARLES F. THIRION.
